[57] CLAIM

The ornamental design for a rear end portion of truck body, as shown and described.

DESCRIPTION

FIG. 1 is a perspective view of a rear end portion of truck body showing my new design;

FIG. 2 is a rear elevational view thereof;

FIG. 3 is a front elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The broken lines in the drawings are provided to illustrate the environment of the claimed invention and do not form a part of the claimed invention.
